By Henry O. Stj

Atty.

UNITED STATES PATENT OFFICE

KARL JOHAN JUNGHOLM, OF STOCKHOLM, SWEDEN

ELECTRICAL SWITCH

Application filed September 18, 1929, Serial No. 393,517, and in Sweden April 19, 1928.

This invention relates to electrical switches and more particularly to electrical switches contained in boxes and combined with plug fuses, of the kind in which the fuse holders are secured to a rotatably mounted part, on the rotation of which the two connection contacts of each fuse can be cut out, and the fuses thus rendered "dead". In the hitherto known constructions of this kind the fuses cannot be cut out, or at least not entirely cut out, before the lid has been opened, so that it is possible to touch the fuses while they are still conducting current. In accordance with the present invention the fuse holders are mounted on a shaft independent of the lid of the box which shaft can be turned by means of a handle located externally of the box in such manner that the fuses can be rendered "dead" before it is necessary to open the lid.

One embodiment of the invention is illustrated in the accompanying drawing in which, Figure 1 is a front view of the box, with part of the front wall and lid removed to show the interior of the box. Fig. 2 is a side elevation of the box and Fig. 3 is a cross section thereof.

Referring to the drawing, the numeral 1 indicates a box having a lid 2 hinged at 3 and held in closed state by a screw or the like, as shown at 4. Rotatably mounted in the side walls of the box 1 is a shaft 5 which carries a handle 6 outside one side wall. The shaft 5 is of a rectangular cross section along most of its length, as shown at 7 to receive double pole switch contacts and holders for associated plug fuses serving as safety fuses. For each plug fuse 8 the shaft carries two arms 9 and 10 shaped at their free ends as knife contacts 11 to engage rigid contacts 12 so as to form a double pole switch for each plug fuse. The rigid contacts 12 are in turn connected to preferably vertically extending bus-bars 13 to which the incoming and outgoing conductors (not shown) may be connected by binding screws 14. The box may be formed with openings, as 15, 16, at its bottom and top to enable a plurality of boxes to be placed in a vertical row and the bus bars of the individual boxes be connected together in a simple way.

One arm, as 9, of each pair of arms 9 and 10 is formed with a lateral projection, as indicated by dotted lines in Fig. 3, to which a contact screw 17 for the fuse plug is secured. The other arm, as 10, carries an internally threaded contact sleeve 18 to receive the fuse plug 8.

The handle 6 is provided with an arm 19 having at its free end a lateral projection 20 to cooperate with a cam shaped portion 21 of the lid 2 in such a way as to prevent the lid from being opened as long as the contacts 11 are in engagement with the rigid contacts 12. With the contacts thus closed the current passes through the plug fuses 8. To switch off the current the handle 6 should be moved in the direction indicated by the arrow in Fig. 2. This will cause the shaft 5 to rotate in the direction of the arrow shown in Fig. 3, thereby opening both the primary and secondary contacts of the plug fuses 8. Only after the handle has been rotated to such an extent as to bring the projection 20 out of the path of the cam 21 the lid can be opened to render the interior of the box accessible for inspection or repair. Similarly, the lid must be closed before the handle can be turned back again to close the contacts 11, 12.

What I claim is:

1. An electrical switch, comprising a box having a lid to permit accession to the interior of the box, a shaft rotatably mounted in said box and projecting with one end outside the box, a handle attached to said projecting end, bus-bars in said box extending substantially at right angles to said shaft, primary and secondary rigid contacts secured to said bus-bars and corresponding movable contacts carried by said shaft, in such a way that both the primary and the secondary contacts will positively be broken simultaneously by rotating the shaft, each pair of movable contacts being arranged to receive a contact screw and a plug for fuses, respectively.

2. An electrical switch, comprising a box having a lid to permit accession to the interior of the box, a shaft rotatably mounted in said box and projecting with one end outside the

box, a handle attached to said projecting end, bus-bars in said box extending substantially at right angles to said shaft, primary and secondary rigid contacts secured to said bus-bars, corresponding movable contacts secured side by side to said shaft and all directed to the same side of the shaft, each pair of such movable contacts being arranged to receive a contact screw and a plug for fuses, respectively.

3. An electrical switch, comprising a box having a lid hinged to the box to permit accession to the interior thereof, a shaft rotatably mounted in said box and projecting with one end beyond one side wall of the box, a handle secured to said projecting end, bus-bars in said box extending substantially at right angles to said shaft, primary and secondary rigid contacts secured to alternate bus-bars, corresponding movable contacts secured to said shaft side by side and all directed to the same side of the shaft, said movable contacts being arranged to receive contact screws and plugs for fuses, and means to prevent the lid from being opened except in the "dead" state of the fuses.

4. The combination with a rotatable switch-blade of an electrical switch, said switch being disposed in the chamber of a box having one side thereof open, a cover hingedly connected to one side of said box, fuse plugs carried by the switch-blade, stationary contacts within the chamber of the box, contact members cooperating therewith and carried by the switch-blade, a handle member carried by the switch-blade, an arm carried by said handle member, said arm overlying an arcuate cam surface carried by the cover and normally maintaining the cover closed, said arm and cam surface being positioned whereby when the switch-blade is rotated to position the fuses adjacent the box opening, said cover will be released.

5. In testimony whereof I have signed my name.

KARL JOHAN JUNGHOLM.
